David and Raymond Patent Firm

(57) **CLAIM**

The ornamental design for an environment control apparatus for cutting machine, as shown and as described.

DESCRIPTION

FIG. 1 is a top, right, front perspective view showing my new design.

FIG. 2 is a top, left, rear perspective view thereof.

FIG. 3 is a front view thereof.

FIG. 4 is a left end view thereof.

FIG. 5 is a right end view thereof.

FIG. 6 is a top view thereof.

FIG. 7 is a bottom view thereof.

FIG. 8 is a top, right, front perspective view thereof, showing an environment of a cutting machine.

FIG. 9 is a top, left, rear perspective view thereof, showing the environment of the cutting machine.

FIG. 10 is a top, right, front perspective view thereof, showing the sliding vacuum hood in the front most position.

FIG. 11 is a top, right, front perspective view thereof, showing the sliding vacuum hood in the rear most position; and,

FIG. 12 is a top, right, front perspective view thereof, showing the actuating chamber rotatably attached to the sliding vacuum in the down most position.

The broken lines in the drawings are for illustrative purposes only and forming no part of the claimed design.

1 Claim, 12 Drawing Sheets
